OF KINGS MOUNTAIN, NORTH CAROLINA

GRAVITY OILING MECHANISM FOR SPINNING FRAMES AND THE LIKE

Application filed June 27, 1929. Serial No. 374,194.

This invention relates to means for lubricating roll stands of spinning frames, roving frames and the like, and provides means for lubricating the bearing portions of a roll stand with a constant and proper flow of lubricant at all times.

An object of my invention is to provide means for feeding a constant and properly regulated supply of lubricant to the bearing 10 of roll stands in spinning frames, roving frames and the like, and more especially to a device adapted to be fitted on to the conventional structure of a roll stand, in such a manner as not to interfere with the operation of 15 the roll stand and associated parts yet at all times to feed a constant and proper supply of lubricating material to the roll stand.

Another object of my invention is to provide an adjustable plate member having a 20 plurality of tubes mounted therein with a wooden member mounted in the bottom of each of the tubes through which the lubricant is adapted to seep thru said wooden member being adapted to ride on top of the 25 bearing portion of roll stands.

Another object of my invention is to provide a plate member adapted to be fitted on the roll stand, said plate member having a plurality of slidably mounted tubes therein 30 with said tubes being closed at their lower ends by a wooden member, through which wooden member a lubricating material is adapted to seep, said wooden members being adapted to press by their own weight against 35 the bearing portion of the roll, and the lubricant being adapted to be placed in the tubular members and to seep downwardly through the wooden member and be deposited on the bearing portion of the roll.

40 Some of the objects of my invention having been stated other objects will appear as the description proceeds, when taken in connection with the accompanying drawings, in which—

45 Figure 1 is a cross-sectional view taken along the line 1—1 in Figure 2;

Figure 2 is a plan view of a roll stand showing my invention applied thereto;

50 Figure 3 is a cross-sectional view taken along the line 3—3 of Figure 2.

Referring more particularly to the drawings the numeral 10 indicates a roll stand which has the bearing portion 11, in which the front roller 56 is adapted to be mounted and slidably and adjustably mounted on the portion 10 is the bearing portion 12 which has the two journal portions of rolls 13 and 14 mounted therein, and this member 12 is penetrated by the bolt 15, which is adapted to be adjusted in the slot 16 in the member 10 so that the two upper rolls can be adjusted with relation to the front or lower rolls.

At the upper end of the member 12 there is pivotally mounted the rods 17 and 18 which run from one roll stand to another, and these rods have integral therewith the arms 19 and 20 which project downwardly and rest on the roll stand cover and these arms have slidably and adjustably secured to the lower end thereof the portions 21 and 22, said portions 21 and 22 having the upwardly projecting lugs 23 and 24 and the members 19 and 20 are adapted to be adjusted with relation to the members 21 and 22 by means of the bolts 25 and 26.

This structure thus far described is the conventional structure in roll stands, but I desire to attach to said structure my invention which comprising the plate member 30 which has slidably and adjustably mounted thereon the plate member 31, which has the slots 32 and 33 therein, and the set screws 34 and 35 are threadably mounted in the portion 30, so that by means of the slots and the set screws the portion 31 can be adjusted with relation to the portion 30.

Slidably mounted in the portion 30 are the tubular members 37 and 38, and the member 31 has the tubular member 39 slidably mounted therein.

These members 37, 38 and 39 have the tubular members 40, 41 and 42 fixedly mounted therein, which members have the cover members 43, 44 and 45 mounted thereon, said cover members being adapted to be raised upwardly when a lubricant is desired to be inserted into the tubular members 37, 38 and 39. When these members 43, 44 and 45 are raised upwardly they strike the projections 50, 51 and 52 which prevent their being raised

any further, so that when the oil can is removed from the oiling operation the lids 43, 44 and 45 will fall back to closed position.

Fixedly mounted in the bottom of the tubular members 37, 38 and 39 are the wooden members 53, 54 and 55 through which the lubricating material is adapted to seep and be conveyed to the roll portions 13, 14 and 56.

The member 31 has the downwardly and inwardly turned member 60 which is adapted to press against the member 39 so as to adjust the same as to its position with relation to the member 31 and to cause the portion 55 to fit properly on the front roll stand bearing 56.

It is desired to be noticed that the members 30 and 31 form a straight plate on the bottom side thereof which fit against the members 19 and 20 and form a cover for these members and prevents lint from falling downward into the bearing portion which serves a double purpose, in that it gives a proper lubrication to the roll stand bearing, and prevents lint from falling into the roll stand bearing.

The member 31 has the cut away portions 63 and 64 which are adapted to fit over the members 22 and 23 and prevents the plates 30 and 31 from sliding downwardly, but holds them in proper position with relation to the roll stand bearings.

In the drawings and specification I have set forth a preferred embodiment of my invention, and although specific terms are employed they are used in a generic and descriptive sense only, and not for purposes of limitation, the scope of the invention being set forth in the appended claims.

I claim—

1. In a lubricating device for roll stands and the like, a plate member adapted to fit on top of the roll stand, said plate member being in two sections and adjustable as to length, a plurality of tubular members mounted in said plate member in a slidable manner, said tubular members being adapted to receive a lubricating material, vegetable plug members mounted in the lower ends of said tubular members and being adapted to press against the bearing portion of the journals mounted in said roll stand.

2. In a lubricating device for roll stands, two plate members adjustably secured to each other, a plurality of tubular members slidably mounted in said plate members, a cover for each of the said tubular members, a wooden plug member mounted in the lower end of said tubular members, said wooden plug member being adapted to press against the journal portions of the rolls in said roll stand to pass a lubricant from the tubular members to the said journal portion.

3. In a lubricating device for the journal portions of rolls in a roll stand for roving frames, spinning frames and the like, a plate

member adapted to rest on top of the roll stand, a second plate member adjustably mounted on the first plate member, a plurality of tubular members mounted in a slidable manner in said plate members, a wooden plug for the bottom of each of the tubular members, said wooden plug being adapted to rest on the journal of the rolls in the roll stand, said tubular members being adapted to receive a lubricant and said lubricant being adapted to seep through the wooden members to lubricate the journal portion of the rolls in the roll stand.

4. In a lubricating device for spinning frames, roving frames and the like, a plate member adapted to rest on a portion of the spinning frame above the roll stand bearing, a second plate member lying in the same plane and adjustably mounted on the first plate member, a plurality of tubular members mounted in both plate members and being adapted to receive a lubricant, a wooden plug member mounted in the lower end of each of the tubular members, and being adapted to rest on the journal of the rolls in the roll stand, whereby a liquid lubricant is adapted to be deposited in the tubular member and to seep through the wooden plug member in the lower end of said tubular members.

5. In a lubricating device for the journal bearings in roll stands, of spinning frames, roving frames and the like, a plate member adapted to rest above the roll stand, a second plate member adapted to be adjustably mounted in relation to the first plate member, and having its main portion lying in the same plane with the first plate member, a plurality of slidably mounted tubular members mounted in said plate members and projecting to a point above the journal of the rolls which are mounted in the roll stand, a plug member mounted in the lower end of each of the tubular members, said tubular members being adapted to receive a lubricant, and a cover member for each of the tubular members, said cover member being adapted to automatically close by its own weight when raised to permit a lubricant to be inserted into the tubular members, and after the liquid has been inserted into the tubular members and the liquid depositing member has been withdrawn.

6. In a lubricating device for roll stands and the like, a plate member adapted to fit on top of the roll stand, said plate member being in two sections and being adjustable as to length, a plurality of tubular members mounted in said plate member in a slidable manner, a vegetable plug member mounted in the bottom of each of the tubular members, said plug member being adapted to bear against the journal portion of the rolls in a roll stand, a lubricant being adapted to be placed in the tubular members, and to

flow through the plug members by gravity and the pressure of the oil on the plug member.

7. In a lubricating device for the journal bearings in roll stands of spinning frames and the like, a plate member adapted to rest above the roll stand, a second plate member adapted to be adjustably mounted with relation to the first plate member, and having its main portion lying in the same plane with the first plate member, a plurality of slidably mounted tubular members mounted in said plate members and projecting to a point above the journal of the rolls which are mounted in the roll stand, a plug member mounted in the lower end of each of the tubular members, said tubular members being adapted to be filled with a lubricant and said lubricant being adapted to force its way through the plug members by gravity, and the weight of the lubricant being adapted to cause the plug members to press at all times against the journal of the rolls mounted in the roll stand.

25 In testimony whereof I affix my signature.
WILLIAM C. McGEE.
